UNITED STATES PATENT OFFICE.

WILLIAM MAYOR, OF EAST CLEVELAND, OHIO.

PORTABLE FURNACE.

1,408,624.

Specification of Letters Patent.

Patented Mar. 7, 1922.

Application filed November 3, 1920. Serial No. 421,444.

To all whom it may concern:

Be it known that I, WILLIAM MAYOR, a citizen of the United States, residing at East Cleveland, in the county of Cuyahoga and State of Ohio, have invented a certain new and useful Improvement in Portable Furnaces, of which the following is a full, clear, and exact description, reference being had to the accompanying drawings.

10 This invention relates to furnaces and is directed more particularly to portable furnaces such as are used in connection with drying ovens and similar structures.

15 Some of the objects of the present invention, are to provide a furnace of the aforesaid character which shall be highly efficient, simple in construction and inexpensive to build; to provide a furnace which shall have a small grate area and yet be capable of replacing the source of heat using a large 20 grate area usually found in connection with drying ovens and similar structures; to provide a furnace which may be conveniently and easily applied to existing types of ovens 25 without involving expensive changes in construction; to provide a furnace which shall be a self contained unit and be capable of many uses, while further objects and advantages will appear as the description proceeds.

30 In the accompanying drawings wherein I have shown an illustrative embodiment of my invention but without intent to limit myself thereto, Fig. 1 is a front elevation of a furnace constructed in accordance with my 35 invention; Fig. 2 is a top plan view thereof; Fig. 3 is a side elevation illustrating my furnace connected to a drying oven; Figs. 4 and 5 are sectional views taken on the lines 4—4 and 5—5 respectively of Fig. 2; Fig. 6 is a 40 sectional view taken on the line 6—6 of Fig. 5; Fig. 7 is a sectional view taken on the line 7—7 of Fig. 6 and Figs. 8 and 9 are vertical and horizontal sectional views of a drying oven showing my furnace applied thereto.

45 Heretofore drying ovens and similar structures have usually been heated by a grate built directly in such structures. Grates of this character are necessarily of a 50 large area to assure even heat within the oven and consequently require a large

amount of fuel. Furthermore, ovens heated in this manner circulate the heat to a very small extent and the steam, generated from the drying articles, condenses on the walls of the oven and hence requires additional 55 heat to convert it again into steam before it is finally driven from the enclosure.

With a furnace built in accordance with my invention, I use a small grate area and by means of a forced draft beneath and above 60 the grate I promote complete combustion of the fuel and direct the current of hot air into the oven adjoining the furnace. The current of hot air passes over the articles, quickly drying them and carries the steam 65 up the flue connected with the oven. I am thus enabled to dry the articles in less time and with less fuel with a furnace of this nature.

70 A furnace constructed and used in accordance with my invention is shown in the accompanying drawings wherein 1 indicates the combustion chamber which has a series of perforated grate bars 2 disposed adjacent the lower end thereof as shown in Figs. 75 4—7. The side walls 4 and 5, which are composed of fire brick, are provided, each adjacent its outer edge, with a pair of upwardly extending flues 6—6 which are directed at their upper ends into the combustion chamber 1. The flues 6 are closed on their fourth 80 side by a suitable metal casing 7 which encloses the side walls 4 and 5 and the front wall 8 of said furnace. The lower ends of the flues 6 connect with a passage 9 disposed beneath the grate and which extends transversely of the furnace beneath the walls 4 and 5 as shown in Figs. 5 and 7. The side walls are also provided each with an opening 10 above, and an opening 11 below the 85 grate which may be closed in any suitable manner as by means of a sliding door 12. The openings 10—10 are for the purpose of removing clinkers and gaining access to the fuel above the grate while the openings 90 11—11 permit convenient removal of the ashes from beneath the grate.

95 The front wall 8 which is composed of fire brick, has formed therein a suitable firing opening 14 which is normally closed by 100

a door 15 hinged as indicated at 16, said door being formed on the outer face with a series of grooves 17 to permit even expansion thereof. A forced draft is created by a fan 18 which may be driven in any suitable manner, as by an electric motor 19, said draft being conducted to the under side of the grate by a pipe 20 and introduced into the passage 9 at right angles thereto. Regulation 10 of the draft is accomplished by a damper 21 located in the pipe 20.

The rear side of the furnace, indicated by the reference numeral 22, is provided with an outlet opening 23 to permit the hot air 15 from said furnace to be directed into a drying oven or similar structure as shown in Figs. 3, 8 and 9. To facilitate the removal of clinkers and afford a convenient means for inspecting the grate, the top of the furnace 20 is formed with an enlarged opening 24 which is normally closed by a door 25. The door 25 is provided at one end thereof with a transverse rod 26 which is hingedly fastened in the slotted ears 27-27 rising 25 from each side of the furnace, and at the other end, said door is provided with a suitable handle 28. By the slotted hinge connection as shown in Fig. 3 I provide a simple and efficient means for relieving the expansion 30 and contracting of the various parts and thus retain the door in tight relationship with respect to the opening 24 at all times.

In operation, the furnace is charged 35 through the opening 14 and the draft regulated by the damper 21. The forced draft will blow up through the perforated grate and also up through the flues and over the top of the fire insuring complete combustion. Since the air draft is introduced at right 40 angles to the passage 9, the grate will receive the proper draft before the excess air escapes up the flues 6. The heated air leaves the furnace through the opening 23 and is directed into the structure to be 45 heated, which in the present instance, is shown as a drying oven (Figs. 8 and 9). As indicated by the arrows, the hot air is admitted to the oven through a series of openings 30 from whence it passes over the 50 articles to be dried and then leaves through the discharge openings 31-31 regulated by dampers 32-32, to the flue indicated at 33. With a furnace of this type I am enabled 55 to inject a continual current of hot air through the oven and thus dry the articles in a minimum of time. As shown in Figs. 1 and 3, I provide suitable openings 35-35 in the pipe 20 which may be opened when the furnace is shut down and thus permit 60 any back draft of heated air to escape before reaching the fan motor windings and causing any injury thereto.

Having thus described my invention what I claim is:

65 1. A furnace of the class described com-

prising a combustion chamber, a grate arranged within said chamber, a transverse passage extending beneath said grate and having an air duct connected thereto, flues connected with said passageway and opening 70 into said combustion chamber above said grate, means for creating an air draft in said duct, and means for conducting the heated gases from said furnace.

2. A furnace of the class described comprising a combustion chamber, a grate arranged within said chamber, a transverse passage extending beneath said grate and having an air duct connected at right angles 75 thereto, flues connected with the ends of said passageway and opening into said combustion chamber above said grate, a firing opening 80 formed in said furnace at right angles to said flues, means for creating an air draft in said duct, and means for conducting the 85 heated gases from said furnace.

3. A furnace of the class described comprising a combustion chamber open at the top thereof and having a perforated grate adjacent the lower end thereof, a door normally closing the top of said chamber, a transverse passage extending beneath the 90 grate and side walls of said furnace, a plurality of flues connecting said passageway with the upper portion of said combustion chamber, an air draft inlet connected with 95 said passageway at right angles thereto and means for conducting the heated gases from said furnace.

4. A furnace of the class described comprising a combustion chamber open at the top thereof and having a perforated grate adjacent the lower end thereof, a door normally closing the top of said chamber, a transverse passage extending beneath the 100 grate and side walls of said furnace, openings through said side walls connecting with said passage and with said combustion chamber above said grates, flues connecting 105 said passage with the upper portion of said combustion chamber, an air draft inlet connected with said passage at right angles thereto, and means for conducting the heated 110 gases from said furnace.

5. In a furnace of the class described, the 115 combination with a combustion chamber open at the top thereof and having a perforated grate adjacent the lower end thereof, of a door normally closing the top of said chamber, means for retaining said door in 120 tight relationship with respect to said opening at varying temperatures and means for injecting an air draft above and below said grate.

6. In a furnace of the class described, the 125 combination with a combustion chamber, of a perforated grate positioned in said chamber, a passage beneath said grate having flues at each end thereof connecting with said combustion chamber above said grate, 130

and means for introducing an air draft into said passage at right angles thereto.

7. In a furnace of the class described, the combination with a combustion chamber, of a perforated grate positioned in said chamber, a passage beneath said grate, flues connecting the ends of said passage with the top of said combustion chamber, an air

duct inlet opening beneath said grate and an outlet opening adjacent the top of said combustion chamber, said openings being disposed at right angles to said passageway and said flues.

In testimony whereof, I hereunto affix my signature.

WILLIAM MAYOR.
